DRESS TRIM

La Zona McClintock, Enid, Okla.

Application September 27, 1947, Serial No. 776,595

1 Claim. (Cl. 2—278)

1

This invention relates to new and useful improvements in strip-form textile trim for use on millinery, garments or wherever found decoratively useful.

The object of the invention is to obtain a new article of manufacture so constituted that the same is comprised merely of a pair of like standard braids, of a kind readily purchaseable on the open market, whether alike in coloration or wholly or predominantly different in color, thereby to produce a novel article having a uniquely attractive decorative effect.

The braid employed is what is sometimes called serpentine braid, but the same is more generally known today as rick-rack trim. This braid is so woven that it has a zig-zag continuity along its length, which zig-zagging is self-sustaining and so persists during the life of the braid.

The new article of manufacture is made simply by effecting an interweaving or intertwining engagement between the two braids. This is done by arranging the successive portions of one braid which extend in opposite directions obliquely relative to the general line of extension of that braid so that said portions are laid flatwise across the successive similar portions of the other braid. As a result solely of this step, it was discovered that the two braids become permanently edge-wisely interlocked at two points along each such portion of each braid. The new article, which may be designated a duplex rick-rack trim, has an unusual and novel surface appearance, which is very marked indeed when the two braids are wholly or predominantly of different colors; and the new article, further, has a distinctive serpentine shape along its two sides over its entire length.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a composite view showing short lengths of the two like rick-rack braids of the familiar kind.

Fig. 2 shows on an enlarged scale a length of the new duplex rick-rack trim constituted by the two braids of Fig. 1.

Fig. 3 is a perspective view showing an end portion of the new article, with the two braids partially disengaged.

Referring to the drawing more in detail, the 55

2

braid 10 of Fig. 1 is, as is well known, characterized by a zig-zag continuity, composed of regularly alternating portions 11 and 12. Every portion 11 and 12, the two adjoining ones of which may be considered to provide a zig-zag unit, extends obliquely and at an angle of about 45° to the general line of extension of the braid. Thus each portion 11 is at about a 90° angle to the adjoining portion 12, and vice versa. Each joinder of a portion 11 and a portion 12 at a point inset from one side of the braid will be called a re-entrant recess 14, and each joinder of a portion 12 with a portion 11 at a point inset from the opposite side of the braid will be called a re-entrant recess 15.

The braid 16 of Fig. 1 is exactly like the braid 10. The oppositely inclined portions of the zig-zag units of the braid 16 are marked 17 and 18. The recess resulting from each joinder of a portion 17 with a portion 18 at a point inset from one side of the braid 16 is marked 19, and the recess resulting from each joinder of a portion 18 with a portion 17 at a point inset from the opposite side of said braid is marked 20.

When the two braids are interwoven or intertwined, to effect locking engagement between their recesses, the new article of Fig. 2 is produced. In thus making the new article of the two braids of Fig. 1, and assuming the start of the intertwining is at the ends of said braids at the left in Fig. 1, first the two recesses 14 and 19 diagrammatically coupled by the vertical dot and dash line 21 of Fig. 1 are interengaged, then the two recesses 15 and 20 diagrammatically coupled by the vertical dot and dash line 22 of Fig. 1 are interengaged, then the next two pair of recesses 14 and 19 are interengaged, then the next pair of recesses 15 and 20 are interengaged, and so on. When all the recesses along the lengths of both braids are so engaged, they become interlocked against casual or accidental disengagement; as will become understood when it is noted that a lateral pull on either side of the new article in a direction to cause disengagement of any one pair of interengaged recesses is effectively opposed by a tightening up of a next adjoining pair of interengaged recesses.

In thus physically coupling the two braids by way of their oppositely facing recesses, to complete the new article as in Fig. 2, all that is required is, with the two braids arranged to have their flats generally maintained substantially parallel, first to move one of the braids edge-wisely relative to and in one direction laterally of the other to effect one of the aforesaid en-

gagements, then to move the last mentioned braid edgewise relative to and in the opposite direction laterally of the latter to effect the next of said engagements, and so on.

The braids 10 and 16 thereby are progressively interwoven or intertwined, and in such manner that every portion 11 of the braid 10 flatwise crosses a different portion 17 of the braid 16, and every portion 12 of the braid 10 flatwise crosses a different portion 18 of the braid 16, and also in such manner that, at either side of the new article, according as a portion overlies or underlies a portion 17, a portion 12 underlies or overlies a portion 18.

The side of the new article shown in Fig. 2 is the side thereof showing the portion 17 of the braid 16 overlyingly crossing the portions 11 of the braid 10, and with the portions 18 of the braid 16 underlyingly crossing the portions 12 of the braid 10. Thus in Fig. 2, all the portions 11 are substantially hidden, except for that one thereof there indicated in broken lines and the part of the one thereof fragmentarily seen at the left of Fig. 2. This relationship of the parts is pictorially made fully clear, however, at the left side of Fig. 3.

While I have illustrated and described the preferred embodiment of my invention, it is to be understood that I do not limit myself to the precise construction herein disclosed and the 30

right is reserved to all changes and modifications coming within the scope of the invention as defined in the appended claim.

Having thus described my invention, what I claim as new, and desire to secure by United States Letters Patent is:

A new article of manufacture comprising a pair of flat ribbons, each of said ribbons being zig-zagged laterally forming alternate portions 10 extended at angles of 90 degrees with relation to each other forming alternate reentrant recesses along opposite sides of each ribbon, said ribbons being interlaced to form a flat composite ribbon with the recesses extended inward from opposite sides of the ribbons interengaged and the portions of the ribbons which extend in opposite directions flatwise passing alternately over and under one another.
